Attorney

UNITED STATES PATENT OFFICE.

WILLIAM SEVERN, OF CHICAGO, ILLINOIS.

HANDLE-ATTACHING MEANS FOR MOPS.

1,134,915.

Specification of Letters Patent.

Patented Apr. 6, 1915.

Application filed October 22, 1913. Serial No. 796,301.

To all whom it may concern:

Be it known that I, WILLIAM SEVERN, a citizen of the United States, residing at Chicago, in the county of Cook and State of Illinois, have invented certain new and useful Improvements in Handle-Attaching Means for Mops, of which the following is a specification.

My invention relates to improvements in mops, preferably those known as polish mops, for removing dust from, and renewing the luster of finished floors, wood-work, linoleum, and the like, and has particular reference to novel means for adjustably connecting the handle with the head of the mop, whereby the handle may be moved to various angular positions with relation to the mop head and the mop head conveniently manipulated.

An important object of this invention is to provide novel handle-attaching means to connect the handle with the mop head for permitting the handle to be angularly moved with relation to the mop head and to hold the same in adjustment at desired angular positions with relation thereto.

A further object of the invention is to provide handle-attaching means of the above mentioned character, which are self-adjusting, whereby the necessity of soiling the fingers or hands by contact with a part or parts of such handle-attaching means is avoided.

A further object of the invention is to provide means of the above mentioned character, which are simple in construction, strong, durable, convenient in use, and inexpensive to manufacture.

Other objects and advantages of this invention will be apparent during the course of the following description.

In the accompanying drawings forming a part of this specification and in which like numerals are employed to designate like parts throughout the same, Figure 1 is a perspective view of the mop head and handle connected therewith, by my improved handle-attaching means, Fig. 2 is a side elevation of the same, parts being broken away, Fig. 3 is an end elevation of the handle-attaching means, taken upon line 3-3 of Fig. 1 and looking in the direction of the arrows, Fig. 4 is a transverse sectional view taken on line 4-4 of Fig. 1 and looking in the direction of the arrows. Fig. 5 is a side

elevation of one element of the handle-attaching means, parts thereof being broken away, Fig. 6 is a side elevation of the co-acting element of the handle-attaching means, and, Fig. 7 is a longitudinal sectional view through a sleeve included in the handle-attaching means.

In the drawings, wherein for the purpose of illustration is shown a preferred embodiment of my invention, the numeral 10 designates a mop head, which is preferably triangular, as shown. This mop head comprises a tubular supporting rod or frame receiving portion 11, from which depends a layer or layers of absorbent material 12, preferably formed of cord. The tubular portion 11 is preferably triangular, as shown, for receiving a triangular or angular supporting frame 13, preferably formed of a section of suitably stiff rod or wire. The free ends of the triangular supporting frame 13 extend outwardly beyond the triangular tubular portion 11 at one apex thereof, providing preferably parallel spaced extensions 14, which are preferably arranged in the same horizontal plane with the tubular portion 11. No further description of the mop head 10 is thought to be necessary, it being sufficient to state that the same is preferably of the construction fully described in detail in my co-pending application for polish mops, filed July 17, 1913, Serial No. 779,493.

The numeral 15 designates a handle to be adjustably connected with the mop head 10 by means of handle-attaching means, to be described, and which constitute the present invention.

The handle-attaching means is in the form of a hinge construction 16, comprising co-acting parts or elements 17 and 18, carried respectively by the extensions 14 of the frame 13, and handle 15. The element or part 17 is formed of oppositely arranged plates 19, preferably formed of bending a single section of metal upon itself between its ends. The plates 19 form at their point of bending an extension or stop-lug 20. The plates 19 may be soldered or otherwise attached to each other, if desired. These plates 19 are provided at their lower free ends with sleeves or eyes 21, preferably formed by bending such free ends upon themselves, as shown. The sleeves 21 are rigidly mounted upon the extensions 14 of the supporting frame 13, the ends of these

thus seen that simple and reliable means are provided for securely detachably holding the handle 15 within the sleeve 29.

The co-acting element or part 18 of the hinge construction comprises oppositely arranged spaced plates or disks 27, formed upon converging arms 28, carried by a sleeve 29. The plates or disks 27 are provided with radially disposed locking recesses 30, arranged to receive the locking ribs or lugs 25, such plates or disks being also provided with central openings 31. The plates or disks 27 are arranged outwardly of and in slideable engagement with the plates 19, the lug 20 thereof extending outwardly beyond the same, as shown. The plates or disks 27 are provided adjacent the converging arms 28 with inwardly extending lugs 32, adapted to engage with the lug 20 to positively limit the upward swinging movement of the hinged element or part 18, the downward swinging movement being limited by the engagement of the arms 28 with the sleeves 21.

Passing through the openings 26 and 31 is a transverse bolt or rivet 33, carrying apertured preferably annular sockets or cups 34, there being a clamping or adjusting nut 35 upon one end of the bolt 33. Arranged within the sockets 34 are compressible coil springs 36, which engage the plates or disks 27. It is thus seen that the springs 36 will yieldingly hold the plates or disks 27 in engagement with the plates 19, whereby when sufficient force is applied to the hinge element or part 18 the same may be angularly adjusted with relation to the element or part 17, and locked in adjustment at desired angular positions with relation thereto, by the ribs or lugs 25 fitting within the openings 31 or recesses 30. The sleeve 29 has its contiguous edges provided with a tongue and groove or dove-tail joint 37. The sleeve 29, arms 28, and plates or disks 27 are preferably formed from a single section of suitably stiff sheet metal, which is stamped into the desired shape and subsequently bent to form the different elements.

The handle 15, which may be of any well known or preferred construction, has one end arranged within the sleeve 29 and is provided with a thread groove 39 adjacent the lower end thereof. This thread groove receives a thread 40 formed upon the inner end of the sleeve 29, preferably by bending the material of the same inwardly. It is

thus seen that simple and reliable means are provided for securely detachably holding the handle 15 within the sleeve 29.

In the use of my improved mop the handle 15 may be swung vertically with relation to the mop head, and locked at desired angular positions with relation thereto, by means of the coacting plates 19 and disks 27, provided with the locking ribs and recesses. By having the handle thus angularly adjustably connected with the mop head, the latter may be conveniently manipulated within ordinarily inconvenient or inaccessible quarters, such as within corners, under radiators, furniture or the like. It has been found particularly useful to angularly adjustably connect the handle to one corner or apex of the triangular mop head, owing to the highly convenient manner in which the entire apparatus may be used.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having described my invention, I claim:

1. A device of the character described, comprising a plurality of inner apertured flat plates arranged side by side in engagement with each other, a reduced strip bent upon itself and formed integral with the upper ends of the inner plates to connect them and extending upwardly beyond the same for a substantial distance to serve as a stop shoulder, a plurality of co-acting apertured plates arranged upon the outer sides of the inner plates and provided with upwardly extending fingers to engage with the stop shoulder, a pivot element passing through the two sets of apertured plates, and spring means carried by the pivot element and forcing the two sets of plates toward each other, substantially as described.

2. A device of the character described, comprising a pair of apertured plates arranged side by side in engagement with each other with their lower transverse ends bent outwardly forming elements for engaging mop head attaching means, a supporting member, and yielding pivotal connecting means between the supporting member and the plates whereby the supporting member may be swung to different angular positions with relation to the plates and locked in a selected angular position with relation thereto.

3. A device of the character described, comprising a section of sheet metal bent upon itself between its ends providing integral flat plates arranged side by side in engagement with each other and having their lower ends bent outwardly for prid

viding transverse flanges adapted to engage with mop head attaching means with outwardly bulging ribs stamped from the material of said plates, a corresponding number of co-acting plates arranged outwardly of and adjacent the inner plates and having recesses to receive the ribs and adapted to be connected with a handle, a pivot element passing through the plates to connect them, 10 springs arranged upon the ends of the pivot element, and cups carried by the ends of the pivot element and completely inclosing the springs.

4. A device of the character described, 15 comprising a normally upstanding apertured member provided with ribs, a mop head carrying frame secured to the member, a handle member carrying spaced apertured

plates adapted to be arranged upon opposite sides of the upstanding apertured member 20 and provided with recesses to receive the ribs, a transverse pivot element passing through the upstanding member and plates to connect them, coil springs surrounding the end portions of the pivot element and engaging the outer faces of the apertured plates, and cups carried by the outer ends of the pivot element and engaging and completely inclosing the springs. 25

In testimony whereof I affix my signature 30 in presence of two witnesses.

WILLIAM SEVERN.
